[57] CLAIM

The ornamental design for the solar radiation measuring apparatus, substantially as shown.

DESCRIPTION

FIG. 1 is a perspective view of the solar radiation measuring apparatus showing our new design;

FIG. 2 is a top plan view thereof;

FIG. 3 is a front elevation view thereof; and

FIG. 4 is a right side elevation view thereof.

FIG. 1

FIG. 2

FIG. 3

FIG. 4
